UNITED STATES PATENT OFFICE.

HERBERT E. PERCIVAL, OF SPOKANE, WASHINGTON TERRITORY, ASSIGNOR
OF ONE-THIRD TO MYRON C. PERCIVAL, OF LYNN, MASSACHUSETTS.

CLOTHES-LINE.

SPECIFICATION forming part of Letters Patent No. 370,348, dated September 20, 1887.

Application filed August 16, 1886. Serial No. 210,965. (No model.)

To all whom it may concern:

Be it known that I, HERBERT E. PERCIVAL, of Spokane, Spokane county, Washington Territory, have invented a new and useful Improvement in Clothes-Lines, of which the following is a full, clear, and exact description, reference being had to the accompanying drawings, forming a part of this specification, in explaining its nature.

10 The invention relates to a clothes line having formed therewith or thereon nipping devices for receiving and holding garments or clothes, and said nipping devices, preferably, also forming a part of the line. There are a 15 number of ways in which the line can be made and the same effect or result procured and by substantially the same means, and I have illustrated in the drawings some of these ways.

Referring to the drawings, Figure 1 is a view 20 in elevation representing one form of my invention. Fig. 2 is a view of a line, enlarged, representing a slight change in construction. Fig. 3 is a view in elevation of a line, enlarged, representing another form of construction. 25 Fig. 4 is a section on the line $x-x$ of Fig. 3. Fig. 5 illustrates in perspective another modification of the invention. Fig. 6 illustrates in plan still another form of construction, and Fig. 7 shows another modification of my invention slightly different from that shown by 30 Fig. 2.

A denotes the line, which is provided at intervals with apertures or openings a , formed by outwardly-extending portions a^1 of the wire or 35 metal forming the line. Opening into or communicating with the apertures a are nipping-spaces a^2 , extending lengthwise of the line, these spaces being bounded or formed by the nipping devices or jaws a^3 , which are continuations of the flaring sections a^4 of the outwardly-extended portions a^1 , the said nipping-jaws being formed of portions of the wire or 40 metal extending lengthwise of the line.

In order that the jaws or nipping devices 45 may open or be moved sufficiently apart from each other to allow the insertion of the portion of the article or material to be held by the line from the opening, space, or aperture, it is desirable that the two parts of the wire or section 50 of the line which provide these nippers or jaws should be fastened or secured together at

the end of their straight or nipping sections, and this may be accomplished in a number of ways. There may be jaws or nippers arranged to extend from each side of the opening or aperture a , as represented in Figs. 1, 3, and 6, or they may extend from one side only, as may be desired. Preferably they should be arranged in the line to oppose each other, for the reason which will hereinafter appear.

55 The line may be made of two single and continuous wires, as represented in Fig. 1, and this I consider the best form of construction, as it is the cheapest and probably the most efficient; or it can be made of separate sections 60 united with each other, as represented in Figs. 2, 5. Where continuous wires or rods are used, they can be secured to each other to form the nippers or jaws by twisting, as represented at Fig. 1; or they may be secured together by 65 clips or clasps b , as represented in Fig. 3, or in any other desired way.

In Fig. 5 I have represented the line as made 70 of a number of independent sections, each section of which has an aperture or hole, a , and the nipping device or jaws a^3 , and they are secured to each other by causing the ends of the wire or rod which forms the nippers or jaws to be fastened to the wire or rod which forms the 75 end portion of the recess or hole of the next section, the two ends of the wire or rod of the first section being united by twisting or in any other way. In Fig. 2 I have represented separate sections, each of which has two receiving holes or apertures and two pairs of nippers or 80 jaws, one extending from each hole or aperture, and when thus made the straight parts of the wire or rod which form the nippers or jaws may or may not be united to each other. If the wire is stiff and they are placed closely 85 to each other, as shown in Fig. 7, there is no necessity for uniting them; otherwise it would be well to unite them midway their length by twisting. They are shown as secured together 90 by a link, c , which may be of double or single 95 wire or rod. These variations in construction are described simply to show that the construction of the line can be varied considerably without departing from the essential spirit of the invention; and I would say in this connection that the line can be made of a flat rod or 100 plate of metal and the nippers or jaws and

holes or apertures made by punching out or removing portions of the rod, bar, or plate, as represented in Fig. 6, for it is not essential that the jaws be spring-jaws, although for some purposes it is desirable that they be provided with a yielding movement in relation to each other. The wire or rod of course should be of galvanized metal, or some metal that will not rust or corrode.

10 The advantages of the invention are many, and are too obvious to need special mention.

In use the corner or section of the garment or article is inserted through the opening or aperture *a* and moved between the nippers or jaws, and where it is necessary to suspend the article or garment at two points another corner or section, preferably, should be inserted between the nippers or jaws extending from an aperture or recess in the opposite direction, so that the action of the wind shall tend to draw the ends farther into the recesses and to hold the garment or article upon the line. If the garment or article were placed so that the action of the wind should not tend to draw the corners toward each other and into the apertures or spaces, then the garment or article might become detached.

Having thus fully described my invention, I claim and desire to secure by Letters Patent of the United States—

30 1. A metal clothes-line having at intervals outwardly-extended portions to form openings or apertures *a* for the insertion of the clothing, and nipping-jaws extending lengthwise of the line and forming continuations of the said outwardly-extended portions, substantially as set forth.

35 2. A metal clothes-line having longitudinally-extending nipping-jaws and a series of openings, from both ends of which the said jaws extend, the latter forming nipping-spaces communicating with the said openings, substantially as set forth.

40 3. A metal clothes-line consisting of two wires or rods bent outward at intervals to form 45 openings *a*, and connected together between the said openings, the said line having between the connected portions and the said openings longitudinally-extending nipping-jaws, substantially as set forth.

HERBERT E. PERCIVAL.
